UNITED STATES PATENT OFFICE.

WILLIAM P. PHILLIPS, OF CAMBRIDGE, MASSACHUSETTS.

REGULATING SIGHT-FEED OIL-CUP.

SPECIFICATION forming part of Letters Patent No. 276,069, dated April 17, 1883.

Application filed September 28, 1882. (No model.)

To all whom it may concern:

Be it known that I, WILLIAM P. PHILLIPS, of Cambridge, in the county of Middlesex and State of Massachusetts, a citizen of the United States, have invented a new and useful Improvement in Regulating Sight-Feed Oil-Cups, of which the following is a full, clear, and exact description, reference being had to the accompanying drawing.

This invention relates to the class of oil-cups used upon machinery and engines, consisting of a base having an opening near the bottom, through which can be seen the oil from the lubricator as it is dropped from above onto the portion to be lubricated, and having a body or reservoir for the oil above the base, with a device for regulating the flow of the oil.

My present invention is an improvement upon my regulating sight-feed oil-cup the application for patent upon which was filed in the Patent Office March 13, 1882.

In the drawing the figure represents an upright center cross-section of the oil-cup, in which A is the body; B, the base; C, the upright-stem; D, a check-nut, and E the sight-opening in the base.

In this invention I have produced an oil-cup which has an upright central spindle or stem, upon the lower end of which is formed a valve through which the oil passes in a downward direction to the point to be lubricated. The body of the cup A is preferable glass, and is provided with a metal cover, a, which is made to rest upon the top, and having an aperture in the center through which passes the stem C. Over the top or cover a is placed a check-nut, D. The check-nut is provided with a thread which acts in connection with the thread upon the top of the stem, (represented by b). The bottom of the stem is fitted into an opening made in the base B, and has a duct, y, for the passage of the oil downward, after entering through the valve, which is represented by X. Just below the valve-seat an enlargement is made, (represented by X'), into which the oil first flows after passing the valve X. From X' the oil passes down the duct y, and into a duct made in the base, and represented by z, which duct is a continuation of the duct y, and which carries the oil to the upper part of the sight-feed opening E, through which opening the oil drops from the shoulders z z' to the bearing. The bottom of the stem 55 below the valve X has an external thread, d.

A corresponding thread is cut to receive it in the base B. The top of the base B extends upward in the center, as represented by h, the better to form the valve-connection with the stem, and also to prevent the sediment from 60 the oil from interfering with the working of the valve X. The lower part of the body of the cap A fits over the projecting part of the base h, and is united with the cup by the collar or nut g, the slots or recesses g' being made 65 to receive the wrench or other suitable tool for the purpose of turning the said collar or nut. The projecting part of the base h is threaded externally, as shown by e, upon which the collar or nut fits.

It will be observed that the stem can be raised and held in any desired position by means of the threaded bottom d and the check-nut D. This construction is an improvement over my former invention, in that the 75 valve-stem is operated from the top, and in the novel arrangement of the valve, the duct, and the contiguous opening X', which facilitates the operation of the oil-cup in practical use. It is also a construction which can be manufactured at a low price, and which cannot 80 readily be clogged or get out of order.

Having thus fully described my invention, what I claim, and desire to secure by Letters Patent of the United States, is—

1. An oil-cup consisting of the body A, with a cover, a, the central valve, X, and stem C, provided with check-nut D, and the base B, provided with the sight-feed opening E, and adapted to be secured to the body A by 90 the nut g, all substantially as and for the purposes set forth.

2. In a regulating sight-feed oil-cup, the base B, with perpendicular duct z, and sight-opening E, in combination with a perpendicular valve-stem, C, and valve X, and duct y, substantially as and for the purposes set forth.

3. In an oil-cup, the perpendicular valve-stem C, valve X, and duct y, in combination with the intermediate oil-reservoir, X', substantially as and for the purposes described.

4. In an oil-cup, the valve X and stem C, provided with the screw-thread b and screw-thread d, in combination with the base B, and the check-nut D and cover a, substantially as 105 and for the purposes described.

W. P. PHILLIPS.
